ARTIFICIAL HAIR FORMING DEVICE

Paul Eiberle, Baltimore, Md.

Application March 26, 1947, Serial No. 737,358

3 Claims. (Cl. 132—56)

1

This invention pertains to the making of coiffures and dressing of hair for the head of an individual, especially of a woman, and more particularly to appendages for same to be used with the head hair, that adds to its attractiveness or increases the apparent growth of hair or hirsutic effects on the head of the person. It includes the use of the natural hair of one individual cut or removed therefrom and formed into an artificial hairdo simulating that of the individual who applies it to her head and being suitable for manipulating and insinuating it in such a manner into her own hair as to combine artistically therewith.

There are several known and used ways of making natural hair of individuals into hairdos or coiffure appendages. In one particular system a foundation of bobbinet lace of fine mesh fabric is used. Wisps of hair are knotted to the foundation where the threads cross each other. The wisps of hair are fastened closely together to conceal the said fabric. This type of construction is used for flat matted hair surfaces. In other instances the hair is sewed to a fabric by a sewing machine and a wire rod is inserted in the fabric so it may be bent and remain in a bent condition.

In the above instances, the methods of manufacturing involve considerable skill and tedious labor that makes the finished products relatively expensive. The above methods also are not so effective in holding the hair, and thus the arrangement's life of utility is appreciably reduced. In wearing products produced by the above mentioned methods there is the continual anxiety that the above hair appliances may cause embarrassment which the user feels if the fact that her tresses are artificial becomes accidentally disclosed on the occasion when she wants to appear at her best.

It is therefore, an object of this invention to provide a new and improved coiffure appendage of natural hair for use with the coiffure of an individual, that will avoid one or more of the disadvantages and limitations of the prior art.

Another object of the present invention is to provide a new and improved coiffure appendage of natural hair made up on an artificial frame that can be made up into a form allowing it to be indefinitely shaped and at all times avoid the exposure of the frame on which it is assembled.

A further object of the invention is to provide a new and improved coiffure appendage of natural hair on an artificial frame, that may be assembled easily, quickly and economically, and be flexible enough to appear as a natural hair product before and after use throughout.

A further object of the present invention is to

2

provide a new and improved method of mounting natural hair so it may be used in making artificial flowers or other types of decorations and it may be used as a coiffure appendage.

5 A further object of the present invention is to provide a hair appendage that will be mounted on twisted wire mounting or clips.

A further object of the present invention is to provide a method for producing looped decorations in a continuous manner without showing the joined ends of the materials used in producing said decorations.

Other objects will become apparent as the invention is more fully set forth.

15 For a better understanding of the invention and the objects thereof, reference is made to the appended drawings and the description following. These together outline a particular form of the invention, by way of example and are not 20 a limitation other than set out in the claims which define the scope of the invention.

In the particular form shown in the drawings:

Figure 1 is a front view of an appendage of natural hair formed on a frame and embodying 25 this invention;

Figure 2 is a side view of Figure 1;

Figure 3 is a side view of Figure 1, showing the appendage bent to present a plurality of the appendages;

Figure 4 is a diagrammatic arrangement showing position and form of the hair and wire twisted to hold the loops in place;

Figure 5 is a plan view of the frame used in forming the loops and combining them into a 30 complete appendage, and

Figure 6 is a front elevation of Figure 5;

Figure 7 is an end view of Figure 6.

Similar reference characters refer to similar parts throughout the drawings.

40 The construction shown in the drawings includes a series of flexible metal wires 10 preferably coated with a plastic or other coating having the natural color of the strands of hair 11 to be applied to them. Either the end portions 45 or other selected parts of the strands of hair 11 are laid at right angles against the wires. In this instance the hair is placed between a pair of wires extended horizontally along a relatively flat jig 12 with the wires strung along one of its edges

50 13. The wires are preferably looped and twisted onto the jig at their ends 14 to keep them in place during the construction of the hairdo. The hair 11 is looped around the jig and brought to the wires 10 where it is tied thereon by twisting the wires about it. This is indicated in Figures 4 and 55 6. The wires may be given one or more twists de-

pending on the requirements of the hair and the stiffness desired in the frame 15 produced by the twisted wires. The looping of the hair on the jig 12 and the securing of the latter by the twisted wires is continued until the hairdo is of the desired length. The ends of the strands of hair on the jig 12 are interlaced with new strands of hair to present an unbroken strand. Various shades may be used in the various bunches of hair or other materials used. The end portions 17 of the twisted wires are left free to enable them to be bent into the coiffure of the user or otherwise finished off without unloosening the hair. When the hairdo is completed on the jig 12 to the desired length, and the hair is looped closely along its whole length on the wires, then the whole hairdo is slipped off the jig. This is done by removing the clip 25 from the jig 12. The jig holder 26 has a handle 28 with one end 27 pressed against the rear of the jig. A front jig bearing 28 is formed at the other end of the handle 28 and continues upward to form a longitudinal bearing 29 which is positioned along the top 30 of the jig 12. When the appendage is removed from the jig, the hair is usually arranged in relatively flat loops, which may be opened up or expanded to make the hair take on a more natural wavy appearance. The hair loops are preferably arranged in layers over one another to give them ample body and add to their aesthetic appearance, and allow the hairs 11 to intertwine in among each other. The arrangement allows the hairs to be placed in groups before twisting, as is done in the illustrations. This brings the hairs closer together and gives them a combed appearance. After the hair appendage is completed on the jig and removed therefrom, it is supported by the wire frame arranged inwardly and bent into an arcuate contour to conform with the shape of the head of the user or such other form as may be desirable and made ready for use. Several of the appendages (or rings as they are termed arbitrarily, regardless of their actual shape) may be readily fastened together if desired, and used in that combination. In such cases, the rings may be aligned or placed slightly out of alignment, to suit the situations, and for handling purposes.

The jig 12 is preferably made of plastic or other rigid material having one edge portion 19 bevelled and calibrated to make the loops 20 of hair formed thereon take on an elliptical form and readily determine its length. The wires 11 are brought against the bevelled edge 19, as that portion affords the most convenient place to put and hold them during the assembly of the hairdo thereon. A handle 40 is formed on one end of the jig to facilitate its use, especially when the hairdo is removed. Clamps may be used to join the loops and hold them in position in place of the twisted wires.

While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. A device for the forming of an appendage of artificial hair, comprising a flat jig relatively long with respect to its width, a jig holder resiliently engaging said jig on opposite faces thereof, said holder having an extension along one edge of said flat jig and a clip member encompassing said flat jig and said extension.

2. A device as set forth in claim 1, said flat jig having a tapered edge carrying graduations.

3. A device as set forth in claim 1, said jig holder having a handle portion extending beyond the confines of said flat jig.

PAUL EIBERLE.
